FRANK CAPDEVILA, OF NEW YORK, N. Y.

METHOD AND APPARATUS FOR TREATING HAIR.

Application filed November 28, 1922. Serial No. 603,736.

To all whom it may concern:

Be it known that I, FRANK CAPDEVILA, a subject of the King of Spain, residing at 248 West 45th Street, New York city, in the 5 county of New York, State of New York, have invented certain new and useful Improvements in Methods and Apparatus for Treating Hair; and I do hereby declare the following to be a full, clear, and exact description of the invention, such as will enable others skilled in the art to which it 10 pertains to make and use the same.

This invention relates to a method and apparatus for treating hair and is directed particularly to the provision of certain improvements in the method and apparatus for treating hair which is at present in use for producing what is commonly known as "permanent waving" of the hair.

20 Permanent waving of the hair is accomplished by winding it into tight curls and subjecting these to the action of heat and a suitable reagent until the curls become "set". Then when the hair is released and combed 25 out it takes on the desired wavy appearance.

Heretofore permanent waving of the hair has been produced in the following manner. That portion of the patient's hair which it is desired to treat is first separated into a 30 number of tresses. These tresses are then individually wound upon a device called a "curling stick", usually in the form of a slender metallic rod, and firmly bound, with twine, to each end of the curling stick. Each 35 tress thus wound, or otherwise arranged upon a curling stick, is called a "curl". The curl is wrapped completely with a strip of soft cloth soaked in a solution of some appropriate reagent, and when so wrapped a tube of fibrous material, usually paper, is placed over it. The end of the paper tube nearest the scalp is bound as tightly as possible to the tress to prevent the steam, which is formed later on when the heat is applied, 40 from coming in contact with the scalp and injuring the patient. As an additional precaution against the burning of the scalp, a thin disk of heat-insulating material, such as fibre, is slipped over the tress prior to the application of the paper tube. An electric heater having a circular recess adapted to receive the paper tube is then applied to each of the curls and electric energy applied to the heaters which vaporize the 45 liquid contained in the cloth wrapping and thoroughly steam the hair. After the applica- 50

cation of the heat for a sufficient length of time to cause the setting of the curls the heaters, paper tubes, etc., are removed from the tresses, which, when they are combed out, 60 possess the wavy effect desired.

This method of treating hair, as well as the apparatus employed, possesses certain disadvantages. It is very difficult to apply the paper tubes to the tresses so effectively 65 that hot steam will not escape from the interior of the tubes and cause burning of the scalp. Sometimes the inner end of the tube is moistened so as to soften it and make it possible to bring the tube into closer contact 70 with the hair; and sometimes the paper tubes are provided with an extension of extremely tough, but more pliable, paper than the thick pasteboard tube, which also makes it easier to bind the tube securely to the hair. 75 Various forms of shields, referred to above, are placed next to the scalp, but even when the utmost precautions are taken it occasionally happens that a patient is more or less seriously burned by the steam from some of 80 these paper tubes.

This method of treating hair is also extremely slow and is, in addition, uncomfortable for the patient. The hair which it is desired to curl has to be divided into a certain 85 number of tresses, sometimes as many as fifty. Then each of these tresses must be wound and all of the paper tubes must be applied before any of the tubes can be inserted into the electric heaters which are suspended from the ceiling by means of cords, to which counterbalance weights are secured. This necessitates that the weight of all of 90 these curls encased in the paper tubes must be supported by the head of the patient until the winding of the entire number is completed, and as the weight of each completely prepared curl is quite appreciable the total weight is sufficient to cause considerable 95 discomfort and even pain.

It is inconvenient not to curl the whole length of tress whether it is desired to do so or not inasmuch as according to the present method, the entire tress is necessarily 100 enclosed within the paper tube. Some arrangements for protecting the outer portion of the curl from the steam by means of a non heat-conductive pad have been proposed. In these schemes, however, some heat is bound to affect the portion of the curl 105 which it is desired to protect from it and the result, therefore, is not entirely satis- 110

factory. A further disadvantage of the present method is that it is impossible to make the wave in the hair commence as close to the scalp as desired for the reason that 5 the binding of the paper tube to the tress by means of twine consumes a considerable length of hair in order to make the necessary tight fit between the tube and hair.

It is desirable to devise a method and apparatus by which the above described difficulties will be obviated in so far as possible, and the present invention provides a method in which, after winding the tress upon the curling stick in the usual manner, a portion 10 of the tress so wound, or the entire curl as desired, is placed within a closed treatment chamber provided with pads moistened with a reagent suitable to promote the curling of the hair. Heat is then applied to the tresses 15 or curls thus enclosed. That portion of the tress which it is desired to curl, and only that portion, is exposed to a heated zone, so that where the hair has been previously "waved" and has grown out, leaving a portion 20 of unwaved hair adjacent the scalp, only this unwaved portion need be treated 25 again.

The treatment casing may be adapted to receive only one curl, or it may accommodate any number found convenient and thus the tresses may be wound in groups, each group being placed in the treatment chamber as soon as it is wound, and the treatment casing immediately secured to a suspended heating device to remove the weight from the patient's head. The result 30 of this procedure is to do away with the greater part of the discomfort to the patient because, not only is the weight of the tresses 35 removed from the patient's head almost immediately after each tress is wound, but also the weight of each curl, or wound tress, is materially reduced by reason of the fact that the heavy paper or fibre tubes are dispensed 40 with. Means are provided in my novel treatment casing for preventing the passage of heat through the front face thereof to the scalp, which is in close proximity to this 45 face, as well as for preventing the escape of heat to the scalp at the openings where the tresses enter the casing.

As a further precaution against the scalding heat reaching the scalp I provide a novel combined shield and curl-spacing gauge 50 which is applied to the scalp prior to the application of the treatment casing.

After the tresses are prepared and inserted within the treatment casing, heat is applied to the flat surfaces of the treatment casing 55 in any appropriate manner, however, I prefer to apply heat by means of an electric heater made in two sections so arranged and hinged together that it may be easily applied to the treatment casing, one section in contact with each flat surface of the treatment

casing. Both the heater and the treatment casings are made of material which is a relatively good conductor of heat so that the heat will easily be conducted from the heaters through the walls of the treatment 70 casing to cause the vaporization of the liquid contained in the moistened pads. As these pads are in intimate contact with the curls, the desired heat will be effectively applied 75 to the hair.

If it is desired to treat an extremely long tress the ordinary paper tube is applied to the outer end of the curl which extends through openings in the outer face of the treatment casing and the heat from the 80 treatment casing will pass out into the paper tube and sufficiently heat the portion of the tress contained therein. If it is desired to treat only tresses of relatively short length they will be contained entirely within the treatment casing and the use of these tubes 85 is unnecessary.

The invention further comprises the novel structure and combination of parts described below, for a clear understanding of which reference will be made to the accompanying drawings in which:

Fig. 1 is a view partly in transverse section and partly in elevation of the complete apparatus assembled in position upon a person's head.

Fig. 2 is a view in longitudinal section of the apparatus shown in Fig. 1 taken on line 2-2 of Fig. 1, certain parts being broken away for the sake of clearness.

Fig. 3 is a view in elevation looking at the rear of the apparatus shown in Fig. 2.

Fig. 4 is a plan view of the combined shield and curl-spacing gauge.

Fig. 5 is a sectional view drawn to an 105 enlarged scale to show the joints between the sections of the treatment casing.

Fig. 6 is a view in transverse section taken on line 6-6 of Fig. 2.

Fig. 7 is a transverse section, taken on line 110 7-7 of Fig. 6, to show how the front faces of the casing are pressed together automatically by closing the casing.

Fig. 8 is a view in perspective of the sections of the curl-treating casing separated 115 from each other to show details of their construction.

Figs. 9 and 10 are respectively a plan view and an end view of the treatment casing and heater assembled together.

Figs. 11-13 inclusive, are detail views to illustrate a clamp having double cam surfaces for securing the sections of the casing together.

Fig. 14 is a detail sectional view showing 125 the use of a paper tube in conjunction with the treatment casing when it is desired to treat the entire curl.

Referring now to these drawings and especially to Figs. 1 and 2, the hair 130 having

been gathered from the scalp 14 into a series of tresses 15 is wound tightly upon curling sticks 16 in the usual manner, forming a series of curls 17. These curls 17 have been laid within the treatment casing 18 so that a portion of each curl adjacent the scalp is completely enclosed by the casing, and the outer portions 19 of the curls extend beyond the rear face 20 of the casing, in order that they may not be exposed to the action of the heat. An electric heater 21, comprising sections 22 and 23, is clamped about the treatment casing 18 in operative position to supply heat thereto. This heater 15 is supported by the electric supply wires 24 which pass through the bail 25 attached to the heater at points near the transverse center of gravity of the assembled structure so that it will suspend itself in the desired position approximately as shown in Fig. 1. The supply wires 24 are in the form of a flexible cord which passes over a pulley (not shown) attached to an appropriate support and provided with weights as usual. The 25 complete apparatus for the treating of an entire head of hair comprises a series of the treatment casings and heaters just described, the number of which will depend upon the maximum number of tresses which 30 it is desired to treat. In the particular instance which I have chosen for illustration the treatment chamber is adapted to receive four tresses so that if it were desirable to provide for the treatment of a maximum 35 of fifty tresses it would be necessary to have twelve of these treatment casings and heaters adapted to receive four curls each, and two treatment casings and heaters adapted to receive only single curls. It is 40 desirable to supply each hair treating outfit with a number of treatment casings and heaters for single curls as it very frequently happens that the number of curls desired will not be an even multiple of four.

45 The treatment casing 18 of my hair treating apparatus is made of some good heat conducting material, such as aluminum, and comprises the two complementary sections 26 and 27 which are preferably adapted to telescope one within the other as shown in Figs. 1, 7 and 8. This casing is, in the preferred form of my invention, formed with its inner face 28 substantially conforming to the shape of the head. The depth of 50 the casing from the inner or front face 28 to the outer or rear face 29 is chosen so as to accommodate the average length of curl which it is desired to treat.

The lower section 26 of the treatment casing 60 is provided with a series of marginal slots 30 in the front face 31, and a corresponding series of marginal slots 32 in the rear face 33, the purpose of these slots being to receive the curls 17. The upper section of 65 the treatment casing is also provided with a series of marginal slots 34 which are so located in its inner or curved face 35 as to register with slots 30 when section 27 is placed upon section 26, and as this is done, slots 34 coact with slots 30 to entirely surround the tresses 15. To increase the area of contact between the surfaces of the coacting slots 30 and 34 and the hair of the tresses passing through them, the slots may be angularly disposed as shown in Fig. 8. 70

In order to secure a tight joint between the surface of these slots and the tresses 15, the metal walls 37 (Fig. 5) forming the faces 31 and 35, of sections 26, and 27 respectively, are enveloped with a heat insulating and relatively yielding material 36, such as fibre or the like, and this material is so positioned upon the respective faces of the casing sections that, in the region of slots 30 and 34, this material projects in all places beyond the metallic walls 37 of the casing sections. This construction is shown in detail in Fig. 5, from which it is seen that the hair comes in contact only with the relatively yielding heat insulating material 36 and never touches the metal 37. This figure also shows the relative position of faces 31 and 35 when the top section 27 is telescoped into the bottom section 26 in which position the outer surface of face 35 80 of the top section is pressed against the inner surface of face 31 of the lower section. These surfaces are automatically pressed against each other as the casing sections are telescoped one within the other, by means of the cam surface 38 (Fig. 7 and 8) co-operating with the upper edge of the rear face of the section 26 at the points 39. Double cam clamps 61 (Figs. 11, 12 and 13) 85 are also provided to assist in securing a steam tight fit about the tresses where they enter the treatment casing. These clamps, stamped out of sheet metal, are fastened to upper section 27 by rivets 62 about which they may be rotated by means of handles 63. Projections 64 from the metal face 37 of section 26 extend through the heat insulation 36 into operative relation with the double cam surfaces 65 of clamps 61. These double cam surfaces 65 have two portions; portion 66 (Fig. 13) which is constructed to cause movement of projections 64 in a direction parallel to the axis 62 of the clamp, and portion 67 which is designed to cause motion of projections 64 laterally with respect to this axis. These two devices therefore, i. e. cams 38 and clamps 61, afford ample means both for holding faces 31 and 35 securely together to prevent the escape of steam between them, and, as well, for clamping slots 30 and 34 around the tresses, to prevent leakage of steam there. 90

A window 40 may be provided in one surface of the treatment casing through which the progress of the treatment process may be 95 100 105 110 115 120 125 130

observed, and the rear face of upper section 27 is provided with a depending flange 41 which extends downwardly to partially close the slots 32. Relatively shallow slots 32' (Fig. 8) may be cut in the edge of this flange 41 to register with slots 32 if desired, but the closeness of the fit of the openings formed by the coaction of slots 32 and flange 41 around the curls is not of importance because if the fit is relatively loose it will allow for the escape of vapor or steam from the casing when the heat is applied. As a further means of allowing for the escape of steam, vent holes 42 may be made in the cover 27 adjacent the lower ends of the curls where considerable moisture is likely to accumulate and a relatively large amount of steam form.

By referring now to Fig. 6 of the accompanying drawings we may see the relative position of the various parts of the apparatus and the construction of the electric heater. The curls 17 on the curling sticks 16 are here shown in intimate contact and substantially surrounded by pads of cloth, felt or the like, which are moistened with a suitable treating agent, and which are placed, one in the bottom and one in the top of sections 26 and 27. As before mentioned, the electric heater comprises two sections 22 and 23 of metal, hinged together at 44 so as to clamp the treatment casing between the heater sections. Each of these heater sections is provided with heating coils 45 of any appropriate construction, but usually consisting of some well known resistance wire wound about a mica support and having mica sheets 46 to insulate the layers of coils from each other and from the metal casing. These heating coils are disposed close to the inner surfaces of each heating section 22 and 23 and a packing 47 of some nonheat-conducting material, such as asbestos, is disposed on the outside of each of the heating coils. With this construction of heater and with the walls of the heater sections 22 and 23 made of some good heat conducting material such as aluminum a maximum amount of heat will be transmitted through the inner walls of the heaters, through the upper and lower surfaces of the treatment chamber and to the moistened pads 43 and the curls 17.

The heater sections 22 and 23 are provided with handles 48 to facilitate the application of the heater to the treatment casing. These handles may be covered with a heat-insulating material 48' to avoid burning the fingers of the operator. In putting the heater in place on the treatment casing, the heater, suspended from the cord 24, is grasped by handles 48 and, when pressure is applied to these handles, spiral spring 49 is compressed, and the heater sections 22 and 23 open by swinging about the hinge 44 to receive the treatment chamber 18. Upon the release of

pressure upon handles 48 the spring 49 will cause the heater to clamp the treatment casing between the heater sections and hold it there by friction. However, to insure that the treatment casing does not accidentally disengage itself from the clamp heater during the treatment process, tongues 50 are provided on each of the heater sections 22 and 23 to engage coacting grooves 51 (Figs. 8 and 10) in the treatment casing. These tongues 50 may conveniently be made by extending the ends of the members comprising hinges 44 as illustrated in Fig. 10. In order to supplement the action of spring 49 in clamping the heater upon the treatment casing latches are provided at each end of the heater, comprising hooked members 52 adapted to engage pins 53 so as to positively lock together sections 22 and 23 of the clamp heater.

The combined shield and curl-spacing gauge, which supplements the heat insulated face of the treatment casing in preventing a dangerous temperature from reaching the scalp, is illustrated in Fig. 4. This shield comprises a pair of members 54 and 55 of flexible material which possesses good heat insulating properties, such as fibre, bakelite, or the like, which are hinged together at 56. The width of these members is made a little greater than the depth of the curl-treatment casing so as to shield the scalp from the direct heat of the electric heaters, as is shown in Fig. 1. Each of the members 54 and 55 has a plurality of marginal slots, 57 and 58 respectively cut in one edge thereof in such manner that, when the members are moved about hinge 56, so that one member lies substantially over the other, these slots are caused to cooperate with each other to surround the tresses. A single hook-shaped pin 59 is provided near the end of member 55 opposite to the hinge, which is adapted to coat with a series of holes 60 in member 54. By engaging hooked pin 59 with one or another of the holes 60, members 54 and 55 are clamped securely about the tresses, the proper hole 60 to use depending upon the size of the tresses and the amount of clamping pressure desired.

In Fig. 14 an ordinary paper tube 68 is shown in combination with my improved treatment casing (lower section 26 only of which is illustrated) for the purpose of treating a tress or curl of unusual length. A portion 19 of the curl 17 which extends beyond the outer face 20 of the treatment casing is wrapped with a strip of soft cloth 69, which has previously been moistened with the hair treating reagent. The paper tube 68 is then passed over the wrapping 69 and its inner end inserted within slot 32. When the upper section of the treatment casing is now placed upon lower section 26, tube 68 will be firmly held in place, its inner

end being in communication with the interior of the treatment casing so that steam may pass outwardly through the tube to heat and curl the entire length of the tress.

5 In the operation of my apparatus the hair of the patient's head is first separated into tresses, the spacing of which is determined by the use of the combined curl spacing gauge and shield, and this shield is left in position embracing the tresses at points as close to the scalp as possible. The shield, being made of flexible material, will easily conform to the curvature of the head as will be seen by referring to Fig. 2 of the drawings.

10 The tresses, in the form of my invention which I have preferred to illustrate by way of example, are then wound upon the curling sticks 16 in the usual manner, and are 15 immediately laid in lower section 26 of one of the treatment casings, into which has previously been placed a pad 43 moistened with a suitable reagent. The other section 27 of the treatment casing, also containing 20 a moistened pad 43, is then placed in position and the two sections firmly pressed together with the fingers. This will cause 25 cam surfaces 38 to force the inner faces 31 and 35 firmly together. While thus held 30 with the fingers clamps 61 are moved to locked position, in which they engage projection 64, so as to draw the two sections of the casing together as well as to supplement 35 the action of the cam surfaces 38 in pressing the faces 31 and 35 together in a lateral direction.

35 A suspended clamp heater 21 is immediately placed upon the treatment casing, to remove the weight from the patient's head, and secured firmly in position by 40 means of the latch members 52 acting in conjunction with spring 49. This group of four curls is now ready for treatment, and as soon as all of the tresses which it is 45 desired to treat are prepared for treatment in a similar way, electric energy is supplied to each of the heaters and the treatment allowed to progress until completed.

50 By the use of a curl treatment casing which is adapted to treat simultaneously a plurality of curls the length of time required to treat an entire head of hair is reduced to approximately one-half of the time required by any of the methods in present use of 55 which I am aware. This is of advantage both to the patient and to the operator. Moreover the structure of my improved treatment casing, which securely embraces the tresses, reduces the liability of injury to 60 the patient by scalding, because the structure of the casing is such as to effectively prevent the passage of heat, either through the openings by which the tresses enter the casing, or through the face of the casing adjacent the scalp. Furthermore, the con-

struction of my improved treatment casing is such that the curl or wave may be started closer to the scalp than when paper tubes are used, bound to the hair with twine, which binding takes up considerable length 70 of the tresses adjacent the scalp.

75 In addition to these advantages the use of the treatment casing of my invention makes it possible to treat only the portion of the hair adjacent the scalp which it is desired to treat, and makes it unnecessary to apply the treatment to the whole length of the hair, whether or not it is desired to do this. By the omission of the relatively heavy paper tubes the weight of the wound tresses is reduced to within comfortable limits, and my treatment casing which contains moistened pads and which is adapted to treat a plurality of curls simultaneously, makes it possible also to omit the wrapping of relatively 80 heavy moist cloth about the tresses before they are placed in the treatment casing, and also makes it possible to relieve even the weight of these rather light curls from the patient's head as soon as each set is wound 85 on the curling sticks.

90 Inasmuch as the treatment casing 18 is made of a metallic material, such as aluminum, it is relatively impervious and will not absorb the reagent used in the treatment process, or substances which may distill off from the hair itself during the process. For this reason my improved process is extremely sanitary as compared with the processes in which tubes composed of paper or other relatively pervious material are 95 used. In addition to being more sanitary a further advantage results in that, by the use of my improved treatment casing, the hair is not bleached during the treatment process, as sometimes happens when paper tubes are used because of the unavoidable presence of bleaching agents in the material of which these tubes are made. Every part of my 100 apparatus may be conveniently and cheaply sterilized for re-use, whereas the paper tubes are not susceptible of sterilization.

105 In the preferred embodiment of the apparatus which I have illustrated and described for carrying out my invention, I have shown a curling stick consisting of a slender metallic rod upon which a tress of hair is wound. It will be readily understood, however, by persons skilled in this art 110 that other devices may be associated with the tress. For example, instead of winding the tress upon a curling stick, it may be clamped between the undulated, or serrated, surfaces of a waving device and then laid within the treatment chamber, and the treatment process may then progress in the same manner as though it were wound upon a slender metallic rod or curling stick. I 115 therefore intend, by the use of the term "curling stick" in the appended claims, to 120 125 130

- include all devices upon which a tress of hair may be wound, twisted, clamped, or otherwise arranged in any desired configuration for the waving or curling of the tress 5 of hair during a hair treatment process. I also intend, by the word "curl," to include a tress of hair which has been wound, twisted, clamped, or otherwise secured, and arranged in any configuration, upon such device.
- 10 I claim:
1. A hair treating device comprising a treatment casing in which a plurality of curls are held in a single plane, the casing having a face substantially conforming to the shape of the head, and means for heating the casing.
  - 15 2. A hair treating device comprising a treatment casing having a plurality of equally spaced openings in opposite faces thereof for receiving a plurality of curls, and means for applying heat to the casing.
  - 20 3. A hair treating device comprising a treatment casing having one face thereof substantially conforming to the shape of the head, and provided with a plurality of equally spaced openings to admit a plurality of curls to the casing, and means for applying heat to the casing.
  - 25 4. A hair treating device comprising a treatment casing for receiving a plurality of curls having a face substantially conforming to the shape of the head, means for heating the casing and means for preventing the passage of heat thru said face.
  - 30 5. A hair treating device comprising a treatment casing having one face thereof substantially conforming to the shape of the head, and provided with a plurality of equally spaced openings to admit a plurality of curls to the casing, means for applying heat to the casing, and means for preventing heat from passing through said face so as to injure the scalp.
  - 35 6. A hair treating device comprising a treatment casing provided with a plurality of openings in one face through which a plurality of curls enter the casing, means for applying heat to the casing, and means for preventing the escape of heat through the openings so as to injure the scalp.
  - 40 7. A hair treating device comprising a treatment casing provided with a plurality of openings in one face through which a plurality of curls enter the casing, means for applying heat to the casing, and common means for preventing the passage of heat through the face and the openings therein so as to injure the scalp.
  - 45 8. A hair treating device comprising a curl-treating casing constructed in complementary sections, each section having a plurality of registering marginal slots into which the curls may be laid and which close around the curls when the sections are fitted together.
  - 50 9. A hair treating device comprising a curl-treating casing having one face curved to fit the head and constructed with telescoping sections, each section having a plurality of slots in its curved face and corresponding slots in the face opposite thereto into which curls may be laid, the slots in the curved face being provided with relatively resilient heat-insulating material, and means for clamping the sections together. 75
  - 55 10. A hair treating device comprising a curl treating casing constructed in telescoping sections, each section being provided with a marginal slot in a face thereof, these slots in the coacting sections being adapted to close around a curl when the sections are fitted together. 80
  - 60 11. A hair treating device comprising a curl treating casing constructed in telescoping sections, each section having a plurality of slots in a face into which the curls may be laid, said slots being provided with relatively resilient heat insulating material, and means for clamping the casing sections together. 85
  - 65 12. A hair treating device comprising a curl treating casing constructed in telescoping sections, each section having a plurality of slots in a face thereof into which the curls may be laid, the inner and outer walls of the slotted faces being lined with relatively resilient heat insulating material, and means for clamping the casing sections together. 90
  - 70 13. A hair treating device comprising a curl treating casing constructed in telescoping sections, each section having a plurality of slots in a face thereof into which the curls may be laid, the coacting surfaces of the slotted faces of the sections being covered with relatively resilient heat insulating material to act as a packing therebetween and as a protection for the curls where they pass through the slots, and means for clamping these casing sections together. 100
  - 75 14. A hair treating device comprising a curl treating casing constructed in telescoping sections, each section having a plurality of slots in a face thereof into which the curls may be laid, the inner and outer walls of the coacting faces of the sections being lined with relatively resilient heat insulating material projecting at all points beyond the marginal edges of the metal faces so as to form a packing between the coacting faces 115 and to form a seal with the hair where it passes through the slots, and means for clamping the casing sections together. 120
  - 80 15. A hair treating device comprising a curl treating casing constructed in telescoping sections, each section being provided with a marginal slot in a face thereof, the slots in the coacting sections being adapted to close around a curl when the sections are fitted together, and means acting to force 125
  - 85 16. A hair treating device comprising a curl treating casing constructed in telescoping sections, each section having a plurality of slots in a face thereof, the slots in the coacting sections being adapted to close around a curl when the sections are fitted together, and means acting to force 130

the slotted faces together and to press the walls of the slots about the curls.

16. A hair treating device comprising a curl treating casing constructed in telescoping sections, each section being provided with a marginal slot in a face thereof, the slots in the coacting sections being adapted to close around a curl when the sections are fitted together, and means for forcing the slotted faces into contact with each other, said means including a cam actuated by pressing the casing sections together.

17. A hair treating device comprising a curl treating casing constructed in telescoping sections, each section being provided with a marginal slot in a face thereof, the slots in the coacting sections being adapted to close around a curl when the sections are fitted together, means for forcing the slotted faces into contact with each other, said means including a cam actuated by pressing the casing sections together, and auxiliary clamping means adjacent the slotted faces for urging said faces into contact.

18. A hair treating device comprising a curl treating casing constructed with telescoping sections, each section having a plurality of slots in one face thereof and corresponding slots in the opposite face into which the curls may be laid, the slots in the face mentioned first being provided with a relatively resilient heat insulating material, and means for clamping the sections together.

19. A hair treating device comprising a curl treating casing constructed in complementary sections, each section having a plurality of registering marginal slots into which the curls may be laid and which close

around the curls when the sections are fitted together, the axes of the registering slots being angularly disposed with respect to one another so as to fit snugly around the curls.

20. A hair treating device comprising a curl-treating casing having opposed heat-conducting surfaces, and a heater therefor having sections provided with heating surfaces, and so hinged together as to clamp the casing between these sections with their heating surfaces in contact with the heat-conducting surfaces of the treatment casing, the casing and heater sections being provided with coacting grooves and tongues, and means for positively locking the heater sections together.

21. A hair treating device comprising a curl treating casing having opposed heat-conducting surfaces, and a heater therefor having sections provided with heating surfaces and so hinged together as to clamp the casing between these sections with their heating surfaces in contact with the heat-conducting surfaces of the treatment casing, the casing and heater sections being provided with coacting interlocking devices, and means for holding said devices in engagement with one another.

22. In a hair treating apparatus, the combination of a curl-treating casing adapted to receive a plurality of curls and having one face curved to conform to the shape of the head, means for heating the casing, and a flexible heat protective shield cooperating with the curved face to prevent heat from burning the scalp.

In testimony whereof I affix my signature.

FRANK CAPDEVILA.
